FOLDER MOUNTING FOR SEWING MACHINES

Filed Nov. 26, 1927

By *Sturtevant, Mason*
Attorneys

UNITED STATES PATENT OFFICE

CHARLES F. RUBEL, OF CHICAGO, ILLINOIS, ASSIGNOR TO UNION SPECIAL MACHINE COMPANY, OF CHICAGO, ILLINOIS, A CORPORATION OF ILLINOIS

FOLDER MOUNTING FOR SEWING MACHINES

Application filed November 26, 1927. Serial No. 235,893.

The invention relates to new and useful improvements in folders for sewing machines, and more particularly to the mounting for a folder.

5 A object of the invention is to provide a mounting for a folder whereby the folder may be quickly removed from the mounting without requiring the removal of screws or other securing means.

10 A further object of the invention is to provide a folder mounting wherein the folder may be removed and quickly replaced on the machine in precisely the same position as it was before it was removed.

15 A still further object of the invention is to provide a folder mounting for sewing machines wherein the folder may be shifted a slight distance away from the needles without detaching the same from its supporting 20 means.

Another object of the invention is to provide a folder mounting for a cylindrical bed machine, wherein the securing means for the mounting is disposed so as not to in any way 25 interfere with the free feed of the material into the folder.

These and other objects will in part be obvious and will in part be hereinafter more fully disclosed.

30 In the drawings which show by way of illustration one embodiment of the invention—

Figure 1 is a side view showing a portion of a sewing machine with my improved 35 mounting for a folder, and with the folder shown in full lines as moved away from the needles without detaching the folder from its supporting means;

Fig. 2 is a sectional view through the work 40 arm showing the folder and its mounting in front elevation;

Fig. 3 is a sectional view through the folder and the mounting therefor, and

Fig. 4 is a perspective view showing the 45 base portion of the folder and the mounting therefor.

The invention is directed broadly to a mounting for a folder, and preferably a folder of the type which is adapted for fell- 50 ing. The folder includes a base portion

carrying an under scroll which guides and folds upwardly and inwardly the lower edge portion of the fabric. Mounted on this base portion is a fabric support carrying an upper scroll, which receives and folds downwardly and inwardly the edge portion of the upper portion of fabric. The two sections of the folder will interfold the edge portions of the fabric and thus form a fell. The folder is secured to a mounting therefor, so that the folder may be shifted on the mounting without detaching it from the mounting. The folder is secured to the mounting through inter-engaging parts formed integral with the folder and the mounting, and no screws or other securing means are necessary. Thus it is that the folder may not only be shifted on the mounting, but may be quickly removed from the mounting, and thus removed from the machine. Then again, the folder may be quickly attached to the mounting, and when attached to the mounting and moved to its forward position, it will have the same position relative to the needles as before it was removed. The mounting is adjustable for varying the position of the folder, but the folder always has a predetermined position on the mounting when in position for forming a fell seam.

Referring more in detail to the drawings, 20 the folder illustrated includes a supporting base 1 which is provided with an under scroll member 2. The fabric is guided along the portion 3 of the supporting base, and the under scroll 2 turns the edge upwardly and inwardly. Removably and adjustably connected to this supporting base is the upper portion of the folder which includes a fabric support 4 for the other section of fabric, and this fabric support 4 carries and leads into an upper scroll 5. The upper scroll 5 is formed with an S-shaped portion 6, and this S-shaped portion is so disposed that the edge of the lower section of fabric extends into the upper recess of the S-shaped portion, 25 while the edge portion of the other section of fabric extends into the lower recess of said S-shaped portion. Thus it is that the fabrics are interfolded to form the fell. After the fabrics pass through the folder, 30

they are led beneath a presser foot 7 and are stitched by a stitching mechanism including needles 8. One or more needles may be used.

The machine to which the invention is applied includes a cylindrical work support 9, and the folder is secured to the work support by my improved folder mounting. This folder mounting consists of a plate 10 which is preferably curved to conform to the upper curved face of the cylindrical work support. This mounting 10 is provided with slots 11, 11. Screws 12 pass through these slots, and are threaded into the work supporting arm 9 for firmly securing the mounting to the work support. The slots are elongated in the direction of the longitudinal axis of the work support, and thus it is that the mounting may be shifted toward or from the needles and secured in adjusted positions through the screws 12. At one side of this mounting 10 is a sleeve 13. The sleeve has the upper portion thereof cut away, forming a stop shoulder 14. The supporting base of one of the folders has an arm 15 formed integral therewith. This arm extends forwardly from the upper front edge of the supporting base, and is thence bent downwardly and extends in a horizontal direction beneath the supporting base so that it may be inserted in the sleeve 13. Said arm conforms in cross section substantially to the opening in the sleeve, and the arm can slide freely in the sleeve, or it can rotate in the sleeve, thus allowing the supporting base to pivot about the sleeve. The arm may be forced into the sleeve until the bent portion of the arm engages the stop shoulder 14, and this determines the extreme inner position of the supporting base on the folder mounting. The arm is partially withdrawn from the sleeve, but is held supported by the forwardly projecting cut-away portion of the sleeve. The other edge of the supporting base is adapted to be passed underneath an overhanging securing plate 16 which is formed integral with the mounting. The folder is brought down into the plane of the recess beneath this securing plate 16 and is then moved toward the needle and beneath the plate. The supporting base of the folder preferably engages the mounting centrally thereof, so that it has to be sprung slightly to pass the outer edge of the supporting base beneath this securing plate. Thus it is that the plate will grip the supporting base so as to hold it in its set position on the mounting. The head of the screw 12 projects above the plane of the base of the folder and serves as a limiting stop to limit the movement of the supporting bracket. This permits the folder to be slipped back along the support and away from the presser foot for the insertion of very heavy work, such as the ends of elastics, heavy cross seams, etc. When it is desired to remove the folder, the left-hand screw 12 is removed. The

right-hand screw will hold the folder mounting in different adjusted positions. The folder may be moved away from the needles on the supporting base and entirely disconnected therefrom. Another folder may be substituted therefor and properly placed relative to the stitching mechanism without loosening the adjustment of the supporting base on the work support. In the placing of the folder, the end of the arm is placed on the extension of the sleeve, which will guide it into the sleeve, and the folder is turned down so that the opposite side or outer portion of the supporting base may pass underneath the supporting plate 16. When the folder is moved all the way in toward the needles, then it engages the stop shoulder 14, and this insures that the folder is replaced in precisely the same position that it was removed from the machine. When it is desired to change the position of the folder relative to the needles, then the screws 12 are loosened and the mounting shifted on the work supporting arm.

It will be noted that the folder can be drawn back a slight distance from the needles, if desired, without removing the folder from the mounting, and this can be accomplished without the necessity of taking out any screws or other securing means.

This mounting makes a very efficient support for a folder on the end of a work supporting arm. The folder and its mounting therefor is particularly well adapted for felling tubular articles, such as sleeves or leg portions of garments.

It is obvious that minor changes in the details of construction and the arrangement of the parts may be made without departing from the spirit of the invention as set forth in the appended claims.

Having thus described the invention, what I claim as new and desire to secure by Letters-Patent, is:—

1. In a sewing machine, a folder having means for interfolding fabric sections, a mounting for said folder, means for securing the mounting to the sewing machine, and means for removably securing the folder to the mounting, said last-named means including inter-engaging parts formed integral with the folder and the mounting, said inter-engaging parts including an arm integral with the folder and a sleeve integral with the mounting adapted to receive said arm, said arm having a pivotal and a sliding engagement with said sleeve.

2. In a sewing machine, a folder having a supporting base, an arm integral therewith, a mounting for said folder, means for securing said mounting to the sewing machine, said mounting having at one side thereof, a sleeve adapted to receive said arm, and at the other side thereof, an overhanging securing plate underneath which the supporting base may be

sprung for securing the folder to the mounting.

3. In a sewing machine, a folder having a supporting base, an arm integral therewith, a mounting for said folder, means for securing said mounting to the sewing machine, said mounting having at one side thereof, a sleeve adapted to receive said arm, and at the other side thereof, an overhanging securing plate underneath which the supporting base may be sprung for securing the folder to the mounting, and a stop for limiting the sliding movement of the folder relative to the mounting so that said folder may be placed in a predetermined set position relative to the mounting.

4. In a sewing machine, a folder having a supporting base, an arm integral therewith, a mounting for said folder, means for securing said mounting to the sewing machine, said mounting having at one side thereof, a sleeve adapted to receive said arm, and at the other side thereof, an overhanging securing plate underneath which the supporting base may be sprung for securing the folder to the mounting, said securing means for the mounting permitting the same to be adjusted in the sewing machine toward and from the stitching mechanism.

30 In testimony whereof I affix my signature.
CHARLES F. RUBEL.
